UNITED STATES PATENT OFFICE.

HENRY D. DESCHLER AND EDMUND H. FRETZ, OF EMAUS, PENNSYLVANIA.

SHUTTER-WORKER.

SPECIFICATION forming part of Letters Patent No. 443,709, dated December 30, 1890.

Application filed May 20, 1890. Serial No. 352,529. (No model.)

To all whom it may concern:

Be it known that we, HENRY D. DESCHLER and EDMUND H. FRETZ, citizens of the United States, residing at Emaus, in the county of 5 Lehigh and State of Pennsylvania, have invented a new and useful Shutter-Bower, of which the following is a specification.

This invention relates to shutter-bowers, and the object thereof is to provide means 10 whereby the shutter may be operated from within the house without raising the window, and may be set at any desired angle and locked in such position. This object we accomplish by our invention, which consists of 15 a special arrangement and adaptation of the well-known rack and pinion, said rack being located within a half tube or gutter passing through the window-frame, and also provided with pins which engage notches in said gutter to hold it set at any desired position therein, and of certain details and auxiliaries of 20 construction, all as hereinafter more fully described, and as illustrated in the drawings, in which—

25 Figure 1 is a horizontal section through a portion of a window-frame, showing our improved shutter-bower in position with the shutter closed. Fig. 2 is a plan view of the rack and pinion in position to lock the shutter open. Fig. 3 is a front elevation of the 30 shutter-bower.

Referring to the said drawings, A is the leaf of the lower hinge, supporting an ordinary shutter, which leaf has a gear-wheel or pinion A' surrounding its pintle. The other leaf of the hinge B is secured to the window-frame and carries the pintle B', and extending from this leaf is a tube C, which passes into the window-frame, as shown, and the upper side of which is cut away, as at c, forming a gutter or half-tube. Through the tubular portion C moves a rack D, whose teeth engage those of the pinion, and pivoted to the inner end of this rack is a bar D', fitting

loosely within the gutter c, extending through 45 the frame into the interior of the house and there provided with a handle or knob E.

The relative arrangement of parts is such that when the shutter is closed, as shown in Fig. 1, the knob E stands against the window-frame, and the joint between the rack D and bar D' stands just inside the inner end of the tube C. We provide the gutter c with a number of notches h in its upper edge, and through the bar D' is seated a pin g, which 50 is adapted to engage these notches. By having several sets of notches it will be readily seen that the shutter may be bowed, opened completely, or closed tightly, and locked in any of these positions by engaging the pin in 55 certain of the notches. The pin is of course disengaged from the notches by raising the knob E, the hole through the inner face of the window-frame being of a shape and size to permit such raising, as will be readily understood.

What we claim is—

In a shutter-bower, the combination, with the shutter having a pinion on its hinge-leaf around its pintle and a tube extending 70 through the window-frame and forming the other leaf of the hinge, the upper half of said tube being cut away for a portion of its length and provided with notches in its upper edges, of a rack-bar moving through said tube and 75 engaging said pinion, a bar pivoted to said rack-bar and moving in said half-tube, a knob on the inner end of said bar, and a pin through the bar engaging certain of said notches, substantially as described.

In testimony that we claim the foregoing as our own we have hereto affixed our signatures in presence of two witnesses.

HENRY D. DESCHLER.
EDMUND H. FRETZ.
